DISCHARGE AND CONNECTING FITTING
MEANS

William C. Groeniger, Columbus, Ohio, assignor
to John B. Pierce Foundation, New York, N. Y.,
a corporation of New York

Application January 11, 1940, Serial No. 313,314

1 Claim. (Cl. 4—13)

The invention relates to improved flush tank discharge and connecting means.

More particularly, the invention is directed to improved fitting means serving dually for affording therethrough the discharge of water or other effluent from a flush tank or equivalent into a toilet bowl or equivalent effluent receiving device and for definitely locating and securely positioning such flush tank or equivalent in supported relation to the toilet bowl or equivalent.

More specifically, the combined discharge and securing fitting means comprises a hollow valve body provided with an inflow opening suitably contoured to serve as the valve seat for a conventional or other approved movable float valve member, the hollow valve body being further provided with one or more flanges or equivalent at its periphery for attachment relative to the walls of the discharge opening of the flush tank and for securement relative to the walls of the inflow opening of the inflow compartment of the toilet bowl or equivalent, combined with mutually spaced elements integral with or otherwise fixed relative to the walls of the hollow valve body, bolt-like member integral with or otherwise secured to such mutually spaced elements arranged to project exteriorly of the walls of the toilet bowl or equivalent, thus disposing of the effective portion of the threading of the bolt or equivalent exteriorly of the path of flow of water or equivalent, attaining effective tightening at initial installation and adjustment at subsequent stages without disturbance of any gasket or other liquid sealing instrumentalities.

Further features and objects of the invention will be more fully understood from the following detail description and the accompanying drawings, in which—

Fig. 1 is a vertical sectional view of the lower portion of a flush tank and supporting rear portion of a toilet bowl, illustrating an embodiment of my combined flush tank discharge fitting and securing means. The flush tank shown in this view is of the conventional bottom outlet valve type.

Fig. 2 is a detail vertical sectional view taken on a plane at right angles to that of Fig. 1, the parts being shown on an enlarged scale.

Fig. 3 is a similar central vertical sectional view of another embodiment of the invention, shown applied to a conventional bottom outlet flush tank. Fig. 4 is a detail top plan view of the combined flush tank discharge and securing fitting illustrated in Fig. 3.

Fig. 5 is a similar central vertical sectional

view of another embodiment of the invention, applied to a conventional bottom outlet flush tank. Fig. 6 is a detail top plan view of the combined flush tank discharge and securing fitting illustrated in Fig. 5.

Referring to Figs. 1 and 2, the flush tank 10 is shown of the conventional bottom opening type, its bottom discharge opening being indicated at 10a. The toilet bowl indicated at 11 may be of any desired construction, provided with a water inlet compartment having an inlet opening at its upper side. Such toilet bowl comprises essentially a chamber 12, for receiving the flushing water, the inlet opening of which is indicated at 13, and a rear shelf 14 of the bowl which is substantially uniplanar and of an area adapted to receive thereupon the flanged bottom 10b of the flush tank 10.

The combined flush tank discharge and securing fitting, designated generally 15, embodying the present invention, is shown comprising the hollow vertically extending discharge body 16, having an upper end opening 16a which may be reduced to receive the vertically extending overflow pipe 17.

The fitting 15 is constructed with suitable means for effecting clamped securement relative to the bottom 10c of the flush tank, as by the provision of a peripherally extending horizontal flange 16b, preferably formed integral with the exterior of the wall of the hollow body 16; such flange is adapted to engage the inner face of the bottom wall 10c of the flush tank 10, preferably through the intermediation of an interposed gasket 16c, which is desirably of rubber or like water-sealing and elastic attributes adapted for porcelain and the like. The lower portion of the hollow body 16 is shown provided with exterior threading 16d for matingly receiving a clamping ring 18, a metal washer and a gasket 18a of rubber or the like being interposed between the ring 18 and the under face of the bottom wall 10c of the flush tank.

Interposed between the lower face of the clamping ring 18 and the upper face of the peripheral wall of the bowl inlet opening 13 is a gasket 18b of rubber or the like. Such gasket 18b is preferably of angular formation, a right angle being illustrated, the lower face of the clamping ring 18 being cut away of corresponding angular formation.

Securement of the discharge valve body 16 relative to the rear shelf of the toilet bowl may be had by variant arrangement. In Figs. 1 and 2, the securement is shown by the provision of the

diametrically extending bar 19, which may be cast or otherwise formed integral at its opposite ends with the opposite walls of the hollow body 16, and provided with a central perforation 19a through which extends a bolt 20, the head 20a of which is non-rotatably received within the recess 19b having a general configuration corresponding to the configuration of the bolt head 20a. The threaded end of the bolt 20 passes through a perforation 12a in the lower wall of the inlet water compartment 12; a flanged annular cylindrical gasket 21 is shown applied about the threaded end of the bolt 20 to project within the bottom opening 12a, and sealingly locked by means of a nut 22, preferably with an interposed washer 23 of metal or the like.

As appears more clearly from Fig. 2, the hollow body 16 is provided with a laterally extending opening 24, and is preferably contoured as indicated at 24a on the arc of a sphere, adapted to function as the valve seat for a spherical movable valve 25, operated and functioning pursuant to the disclosure set forth and claimed in my co-pending application Serial No. 262,669, filed March 18, 1939, entitled Flush valve, now Patent No. 2,229,887, granted January 28, 1941.

The embodiment shown in Figs. 3 and 4 also adapted for a conventional flush tank, corresponds generally to that illustrated in Figs. 1 and 2. The embodiment illustrated in Figs. 3 and 4 comprises, in particular, bars 26, mutually spaced and extending downwardly relative to the lower edge of the hollow valve body 16, meeting at a common central part 26a, from which extends downwardly a bolt-like part 27, the lower end portion 27a of which is shown provided with a threading and sealingly secured in position through the opening 12a of the bowl water inlet compartment 12, as above set forth.

The type of combined tank discharge and securing fitting illustrated in Figs. 3 and 4 is applicable for the conventional ball valve member, its upper end opening being suitably contoured, as indicated at 16e, to serve as a valve seat for such conventional ball valve member. The overflow pipe connected at one side of the fitting, is indicated at 28, its bottom wall being connected to, and preferably integral with, a lateral wall of the hollow body 16, communication between the overflow pipe and the hollow body 16 being afforded by the laterally extending channel 29, having an opening 29a.

The embodiment typified in Figs. 5 and 6 corresponds generally to that of Figs. 3 and 4, but is specific to providing the common central part 26a' with a recess having a lower opening 30 for receiving a headed bolt 31, its head 31a being

received within such recess 26a'', the threaded end of the bolt 31 being sealingly secured in position, through the opening 12a of the inlet water compartment of the bowl, similarly as above. Fig. 5 shows also the employment of a nut 32 applied at an upper threaded portion of the bolt, for securing enhanced locking of the bolt 31 relative to the recessed head locking portion 26a'.

From the above, it is apparent that the fitting and appurtenant parts of the invention in its variant embodiments afford dual objectives, namely a highly reliable mechanical interconnection between the flush tank and the bowl, insuring maintenance of the support of the flush tank upon the top of the rear of the bowl, and the discharge of the flushing water from the tank through the fitting into the inlet compartment or equivalent of a toilet bowl.

Special advantages are attained by the structures afforded by the invention, in that the effective portion of the threading of the threaded member such as a bolt or equivalent is disposed wholly out of the path of the water or other effluent and thus protected from erosion, sedimentation, or other deterioration by water or other effluent; further, the proper tightening of the fitting means at initial installation and at subsequent adjustment is attained by the movement of a nut or equivalent, without disturbance of any liquid-sealing gasket or packing.

Whereas, I have described my invention by reference to specific forms thereof, it will be understood that many changes and modifications may be made without departing from the spirit of the invention.

I claim:

A combined discharge and connecting fitting for securing a flush tank to the top of a toilet bowl, both of which have registering openings 40 for the flow of fluid for flushing the toilet bowl, comprising a hollow member passing through said registering openings, a valve associated with the upper part of said tubular member disposed in the flush tank, said upper part having an exterior 45 flange disposed within the flush tank, an exterior thread adjacent said flange for receiving a nut for securing said tubular member to the wall of the opening in the flush tank, a downwardly extending spider element secured to and within said tubular member, and a solid bolt connection 50 between the central portion of said spider element and a part of the toilet bowl, the bolt nut and the therewith engaged bolt threads being disposed exteriorly of the toilet bowl and away 55 from the path of flow of the flushing fluid, whereby corrosion of said exterior threading and of the bolt threads and nut is prevented.

WILLIAM C. GROENIGER.
